UNITED STATES PATENT OFFICE.

PETER J. BOLAND, OF BERWYN, PENNSYLVANIA.

DANGER SIGNAL.

Application filed July 24, 1922. Serial No. 577,177.

To all whom it may concern:

Be it known that I, PETER J. BOLAND, a citizen of the United States, residing at Berwyn, in the county of Chester and State 5 of Pennsylvania, have invented new and useful Improvements in Danger Signals, of which the following is a specification.

This invention relates to signal devices and has for its object the provision of an 10 illuminated sign or signal device designed for use on highways to be located at cross roads, turns and similar points where driving is dangerous whereby to warn motorists and others that they should slow down, 15 watch out for sharp curves and the like, the device having the great advantage of operating as a preventive of accidents.

An important object is the provision of a sign of this character which may be formed 20 of any suitable number of panels which are adjustably mounted so that the device may be particularly adapted for use at curves of varying sharpness, forks or cross roads, the adjustment of the panels permitting them to 25 be visible from different angles.

Another object is the provision of a device 30 of this character which contains illuminating means whereby it may be seen equally well by night as by day.

Another object is the provision of a device 35 of this character in which the panels are not only adjustable in regard to their angular inclination with respect to one another but which is also provided with means for tilting the panels in case the device is located in a depression or hollow or upon a bank.

An additional object is the provision of a signal device of this character which will be simple and inexpensive in manufacture, 40 easy to install and adjust, positive in action, efficient and durable in service and a general improvement in the art.

With the above and other objects and advantages in view the invention consists in 45 the details of construction to be hereinafter more fully described and claimed and illustrated in the accompanying drawings in which:

Figure 1 is a front elevation of a construction embodying my invention.

Figure 2 is a plan view.

Figure 3 is a rear elevation of one of the panels.

Figure 4 is a vertical section on line 4-4 55 of Fig. 3.

Figure 5 is a plan view of the base plate 11.

Figure 6 is a view of a road showing the manner of using the device, and

Figure 7 is a face view of one of the 60 panels on a larger scale.

Referring more particularly to the drawings, the numeral 10 designates a supporting post which may be a pipe or the like and which in actual practice is preferably 65 embedded in a concrete foundation buried in the ground to a greater or less extent to form a firm base for the signal device. Suitably secured upon the upper end of this post is a base plate 11 having a socket portion 12 fitting on the post. This base plate carries a plurality of upstanding pivot pins 13 and is formed with a corresponding number of arcuate slots 14 concentric with the 70 pins.

The device further includes a plurality of rectangular box like casings 15 formed preferably of sheet metal and provided on their open front sides with glass panes 16 bearing whatever warning legend is desired. 80 Any suitable illuminating means, such as an incandescent bulb 17, is provided within each casing 15 and located within the casing is some sort of reflector 18. The manner of supplying current to the incandescent lamp 85 is a mere detail not described and not shown as being of no consequence.

The mounting for each signal casing 15 comprises an L-shaped bracket 19 and these brackets are formed with holes 20 which are 90 engaged upon the pivot pins 13. Each bracket carries a bolt 21 passing therethrough and engaging within slot 14 for permitting swinging adjustment of the brackets, and these bolts carry nuts 22. The 95 upper ends of the brackets are formed as sockets 23 within which are engaged one end of curved leaf springs 24 which have their other ends secured in sockets 25 which are secured to the backs of the casings 15. 100 Carried by each spring where it is secured to the casing is a threaded rod 26 which passes through a hole in the associated bracket 19 and which carries adjusting nuts 27 which may be turned for the purpose 105 of tilting the casings 15 up or down.

Mounted at the upper corners of the casings 15 are brackets 29 having slotted ends 28 to which are secured signs 30 which are inscribed with legends corresponding to 110

those on the glass panes or panels 16, these signs 30 being designed for day use.

In Figure 6 of the drawings I have shown a plan view of a road having several curves therein, a fork and also a cross road. It is intended that my device be used at these various points as indicated on this view and it will be apparent that at curves it is necessary to use only two of the sign members 15 while at a fork three would be used and at cross roads four will be necessary. Regardless of where the device is used it is obvious that the various sign members 15 may be adjusted upon the base plate 11 by means of the pivotal mounting of the brackets 19 and the slot and bolt means for effecting adjustment. By turning the nuts 27 it is apparent that the sign members 15 may be tilted downwardly and forwardly or upwardly and rearwardly depending upon whether the device be mounted on a bank or in a hollow, the object being to bring the sign members in such position as to insure their being seen by travelers using the road.

From the foregoing description and a study of the drawings it will be apparent that I have thus provided a simply constructed and consequently inexpensive warning sign or signal device which is well adapted for highway use and which will operate as a great safety appliance in preventing accidents by warning and instructing motorists and others in regard to dangerous curves and other conditions necessitating caution.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

1. A device of the character described comprising in combination a base plate, a sign supporting member pivotally supported on said base plate so as to be angularly ad-

justable thereon in a horizontal plane, a sign, connecting means whereby the sign is 50 secured to the sign supporting means with freedom for angular adjustment with reference to a horizontal line running parallel to the plane of the sign and means for securing the sign supporting means and the angularly adjustable sign in fixed position.

2. A device of the character described comprising a support, a base plate mounted thereon, a plurality of brackets rotatably adjustably mounted upon the base plate, and a plurality of tiltably mounted sign members carried by said brackets, each sign member including a casing containing illuminating means and covered by a glass panel bearing warning legends.

3. A sign device of the character described comprising a support, a base plate carried thereby and provided with arcuate slots, upstanding brackets pivoted upon said base plate and carrying clamping bolts passing through the slots for providing rotatable adjustment of the brackets and sign members carried by the brackets, the mounting for the sign members consisting of U-shaped leaf springs secured at one end to the sign members and having their other ends secured to the associated brackets.

4. A sign device of the character described comprising a support, a base plate carried thereby and provided with arcuate slots, upstanding brackets pivoted upon said base plate and carrying clamping bolts passing through the slots for permitting rotatable adjustment of the brackets, and sign members carried by the brackets, the mounting for the sign members consisting of U-shaped leaf springs secured at one end to the sign members and having their other ends secured to the associated brackets, and threaded rods carried by the sign members, passing through holes in the associated brackets and carrying adjusting nuts whereby to effect tilting of the sign members.

In testimony whereof I affix my signature.

PETER J. BOLAND.
